ELECTRIC FLATIRON

Leland H. Snyder, Chicago, Ill., assignor, by
mesne assignments, to Quality Appliances, Inc.,
Chicago, Ill., a corporation of Illinois.

Application November 29, 1944, Serial No. 565,610

6 Claims. (Cl. 38—89)

1

My invention relates to improvements in electric flatiron constructions and particularly to an arrangement for resiliently mounting the handle of the flatiron on the top surface of the sole plate thereof so that the flatiron may be rocked over on its side in a rest position with the sole plate spaced from a support, and it is a general object of my invention to provide an improved construction of this type which may be conveniently handled by domestic users of the flatiron, and which has such a construction as to facilitate the manufacture thereof.

It is another object of my invention to provide an improved resilient connection between the pedestal of the handle portion and the shell of a flatiron construction.

It is a still further object of my invention to provide an improved flatiron construction which will facilitate the rocking thereof on the side of the flatiron when it is placed in a rest position.

Further objects and advantages of my invention will become apparent from the following description referring to the accompanying drawings, and the features of novelty which characterize my invention will be pointed out with particularity in the claims annexed to and forming a part of this specification.

On the drawings:

Figure 1 is a sectional side elevation of an electric flatiron construction which is provided with an embodiment of my invention;

Figure 2 is a perspective view of the resilient connection between one of the pedestals of the handle and the adjacent surface of the top shell of the flatiron construction of Figure 1;

Figure 3 is a top view of the construction of Figure 1;

Figure 4 is a plan view somewhat diagrammatically illustrating the heating coil for the flatiron of Figure 1;

Figure 5 is an end view of the flatiron construction of Figures 1 and 3;

Figure 6 is a view of the flatiron construction of Figures 1 to 5 being rocked over on its side in a rest position;

Figure 7 is a top view of the sole plate of my flatiron construction; and

Figure 8 is a side view partly broken away illustrating the structure for cooling the shell.

Referring to Figure 1 of the drawings, I have illustrated an electric flatiron construction including a conventional sole plate 10 upon which is placed a shell 11. The shell 11 has pointed noses at both ends 12 and 13 as will be seen in Figure 3 and the shell is also provided with a

top surface 14 and similar side portions 15 and 16 as will be seen from an inspection of Figure 5.

Within suitable grooves in the sole plate there is provided a heating coil 17 of any suitable construction having terminals 18 and 19 which are adapted to be connected to any suitable source of power through an electrical cord 20.

The iron is also provided with a pressure plate 21 which is attached to the sole plate by bolts 22 and a thermostat of any suitable construction 23 is provided which has contacts connected to open and close the heating coil circuit in the conventional manner. The thermostat is also provided with a control rod 24 on the outer end of which is provided a dial 25 so that the operator may set the approximate temperature at which the thermostat will operate. The flat iron construction is also provided with a handle 26 formed of any suitable material such as a plastic, the handle being provided with a grip portion 27 and two integrally connected angularly extending pedestals 28 and 29 which are connected to the opposite ends of the grip portion 27.

25 In order to mount the handle 26 to the top surface of the shell 11, surfaces 30 and 31 of the pedestals 28 and 29 are positioned in a manner which will be described below spaced from the adjacent surfaces of the front and rear of the top surface of the shell. In order to mount the handle 26 for limited movement with respect to the shell, studs 32 and 33 extend into bores 34 and 35 of the pedestals with the adjacent ends relatively rigidly attached to the inner surface of the bores by scarfing on the ends of the studs 32 and 33. Opposite ends 36 and 37 extend through bores 38 and 39 in the front and rear of the top surface of the shell, and nuts 40 and 41 are screwed on the cooperating threads on the ends of the studs 36 and 37. By this construction, the handle is mounted for limited movement with respect to the shell, and the amount of this limited movement is controlled by the amount which the nuts 40 and 41 are screwed on the ends of the studs. Furthermore, the nuts provide a stop for limiting the movement of the handle away from the shell.

In order to provide a construction for resiliently biasing independently each of the pedestals 50 28 and 29 away from the shell, a pair of resilient members 42 and 43 are placed in the space between the adjacent surfaces 30 and 31 of the pedestals at the top surface of the shell 11. These resilient members may take any suitable construction, and I have found a very convenient

construction is a reversely bent resilient clip as is clearly shown in Figure 1. Thus, one of the legs 44 is biased against the adjacent surface 30 of the pedestal 28 while the arm 45 of the spring 42 is biased against the adjacent surface of the top surface 14 of the shell 11. The reversely bent spring clip 43 is similarly positioned between the pedestal 29 and the other end of the shell 11. It will also be clearly seen from an inspection of Figure 2 that the spring clip has approximately the same contour as that of the adjacent surfaces of the pedestal. It will therefore be seen that with this construction the operator while ironing can either press the forward pedestal or the rearward pedestal towards the top surface of the shell or both pedestals may be simultaneously moved, and as soon as the operator removes the pressure the spring will return the pedestals to their outward position as is illustrated in Figure 1.

In order to provide a convenient arrangement in which the iron may be rested without bodily lifting it, the sides 15 and 16 of the shell are so constructed as to have longitudinally extending portions 46 and 47. These side portions are so positioned as will be seen from an inspection of Figure 6 that when the iron is rocked over on its side the iron will be supported on a base between the grip portion 27 and either one of the side portions 46 or 47 depending upon which way the iron is rocked. It will furthermore be seen that due to the resilient construction between the handle and the shell as the operator removes his hand from the grip, the grip will drop down onto the base but will do so with a minimum amount of shock due to this resilient connection. It will be understood that by designing the resilient characteristics of the spring for this rocking movement and by allowing the holes in the top surface 14 of the shell to be slightly larger than the diameter of the studs 32 and 33, this limited resilient rocking movement will be allowed.

In order to connect the conductor 20 to the terminals 18 and 19 of the heating unit, a socket construction 50 is provided which extends through an opening 51 in an enlarged portion of the rear pedestal 28. This construction may take any suitable type and in the arrangement illustrated in Figure 1, the electrical cord is permanently connected to the iron due to the shoulders 52 and 53 which tightly surround a restricted portion 54 in the bore through which the socket passes. Also, if desired, a pilot light 55 may be provided in a suitable recessed portion 56 in the front pedestal and conductors 57 connect the light in the electrical circuit in the manner illustrated in Figure 4.

In order to provide an improved construction for minimizing the transfer of heat from the sole plate to the shell so that when the iron is rocked over on its side, the shell will not be sufficiently hot to burn the base upon which the iron is placed, I provide a sole plate construction 60 as is generally indicated in Figure 7 which includes a plurality of shoulder portions 61 through 64. It will be seen from Figure 8 that when the shell is assembled with the sole plate that the lower surfaces of the shell will abut against the shoulder portions 61 through 64 thus leaving passages 65 and 66 through which air may circulate inside the shell. It will also be seen that openings 67 and 68 are provided in the top of the shell through which extend the conductors and air may circulate out through these openings and in between

the legs of the spring clips as is illustrated by the arrows in Figure 8.

Although I have shown and described particular embodiments of my invention, I do not desire to be limited to the particular embodiments described, and I intend in the appended claims to cover all modifications which do not depart from the spirit and scope of my invention.

I claim as my invention:

1. In a flatiron construction having a sole plate and a shell mounted thereon with a top surface and side portions, a handle having a longitudinally extending grip portion and a pair of integral pedestal portions extending angularly from said grip portion at the ends thereof, means including stud bolts having ends relatively rigidly mounted in bores in said pedestal portions and passing through openings in said shell top surface for mounting said handle on said shell with adjacent surfaces of said pedestal and said shell top surface in spaced relation so as to allow limited movement between said pedestal portions and said shell, said side portions of said shell being so arranged that said iron may be rocked over on its side and supported on a base between said grip portion and one of said side portions, with the sole plate spaced from the base, and a pair of reverse bent spring clips between said adjacent surfaces of said pedestals and said shell top surface for resiliently biasing said handle pedestal portions to the limit of their movement away from said shell top surface so that said pedestal portions may be relatively independently moved toward and away from said shell top surface during the ironing operation and to allow for limited rocking movement between said grip portion and said shell when said iron is rocked over to a side rest position on a base between said grip portion and one of said side portions.

2. In a flatiron construction having a sole plate and a shell mounted thereon with a top surface and side portions, a handle having a generally longitudinally extending grip portion and a pair of integral pedestal portions extending angularly from said grip portion at the ends thereof, means including stud bolts having ends relatively rigidly mounted in bores in said pedestal portions and opposite ends passing through openings in said shell top surface for mounting said handle on said shell with adjacent surfaces of said pedestal and said shell top surface in spaced relation so as to allow limited movement between said pedestal portions and said shell, nuts threaded on said opposite ends of said bolts inside said shell for providing adjustable stops for limiting the movement of said pedestal portions away from said shell surface, said side portions of said shell being so arranged that said iron may be rocked over on its side and supported on a base between said grip portion and one of said side portions with said sole plate spaced from the base, and a pair of reversely bent spring clips between said adjacent surfaces of said pedestals and said shell top surface for resiliently biasing said handle pedestal portions to the limit of their movement away from said shell top surface so that said pedestal portions may be relatively independently moved toward and away from said shell top surface during ironing operation and to allow for limited rocking movement between said grip portion and said shell when said iron is rocked over to a side rest position on a base between said grip portion and one of said side portions.

3. In a flatiron construction having a sole plate and a shell mounted thereon with a top surface

and side portions, a handle having a generally longitudinally extending grip portion and a pair of integral pedestal portions extending angularly from said grip portion at the ends thereof, means including stud bolts having ends relatively rigidly mounted in bores in said pedestal portions and opposite ends passing through openings in said shell top surface for mounting said handle on said shell with adjacent surfaces of said pedestal and said shell top surface in spaced relation so as to allow limited movement between said pedestal portions and said shell, nuts threaded on said opposite ends of said bolts inside said shell for providing adjustable stops for limiting the movement of said pedestal portions away from said shell surface, the outer surfaces of said side portions of said shell being so arranged that said iron may be rocked over on its side and supported on a base between said grip portion and one of said side portions with said sole plate spaced from the base, and a pair of resilient means between said surfaces of said pedestals and said shell top surface for resiliently biasing said handle pedestal portions to the limit of their movement away from said shell top surface so that said pedestal portions may be relatively independently moved toward and away from said shell top surface during ironing operation and to allow for limited rocking movement between said grip portion and said shell when said iron is rocked over to a side rest position on a base between said grip portion and one of said side portions.

4. In an electric flatiron construction having a sole plate and a shell mounted thereon with a top surface and side portions, a handle having a generally longitudinally extending grip portion and a pair of integral pedestal portions extending angularly from said grip portion at the ends thereof, means including stud bolts having ends relatively rigidly mounted in bores in said pedestal portions and opposite ends passing through openings in said shell top surface for mounting said handle on said shell with adjacent surfaces of said pedestal and said shell top surface in spaced relation so as to allow limited movement between said pedestal portions and said shell, nuts threaded on said opposite ends of said bolts inside said shell for providing adjustable stops for limiting the movement of said pedestal portions away from said shell surface, and a pair of reversely bent spring clips between said adjacent surfaces of said pedestals and said shell top surface for resiliently biasing said handle pedestal portions to the limit of their movement away from said shell top surface so that said pedestal portions may be relatively independently moved

- toward and away from said shell top surface during ironing operation.
5. In a flatiron construction having a sole plate and a shell mounted thereon with a top surface and side portions, a handle having a generally longitudinally extending grip portion and a pair of integral pedestal portions extending angularly from said grip portion at the ends thereof, means including stud bolts having ends relatively rigidly mounted in bores in said pedestal portions and passing through openings in said shell top surface for mounting said handle on said shell with adjacent surfaces of said pedestal and said shell top surface in spaced relation so as to allow limited movement between said pedestal portions and said shell, and a pair of reverse bent spring clips between said adjacent surfaces of said pedestals and said shell top surface for resiliently biasing said handle pedestal portions to the limit of their movement away from said shell top surface so that said pedestal portions may be relatively independently moved toward and away from said shell top surface during ironing operation.
- 10 6. In a flatiron construction having a sole plate and a shell mounted thereon with a top surface and side portions, a handle having a generally longitudinally extending grip portion and a pair of integral pedestal portions extending angularly from said grip portion at the ends thereof, means including stud bolts having ends relatively rigidly mounted in bores in said pedestal portions and passing through openings in said shell top surface for mounting said handle on said shell with adjacent surfaces of said pedestal and said shell top surface in spaced relation so as to allow limited movement between said pedestal portions and said shell, and a pair of reverse bent spring clips between said adjacent surfaces of said pedestals and said shell top surface for resiliently biasing said handle pedestal portions to the limit of their movement away from said shell top surface so that said pedestal portions may be relatively independently moved toward and away from said shell top surface during ironing operation.
- 15 20 25 30 35 40 45
7. In a flatiron construction having a sole plate and a shell mounted thereon with a top surface and side portions, a handle having a generally longitudinally extending grip portion and a pair of integral pedestal portions extending angularly from said grip portion at the ends thereof, means including stud bolts having ends relatively rigidly mounted in bores in said pedestal portions and passing through openings in said shell top surface for mounting said handle on said shell with adjacent surfaces of said pedestal and said shell top surface in spaced relation so as to allow limited movement between said pedestal portions and said shell, and a pair of resilient means between said adjacent surfaces of said pedestals and said shell top surface for resiliently biasing said handle pedestal portions to the limit of their movement away from said shell top surface so that said pedestal portions may be relatively independently moved toward and away from said shell top surface during ironing operation.

LELAND H. SNYDER.
